UNITED STATES PATENT OFFICE.

MARSHALL ANGLE PURSEL, OF WEST HAVEN, CONNECTICUT.

CALCULATING DEVICE.

Application filed November 10, 1921. Serial No. 514,200.

To all whom it may concern:

Be it known that I, MARSHALL ANGLE PURSEL, a citizen of the United States, residing at West Haven, in the county of New Haven and State of Connecticut, have invented certain new and useful Improvements in Calculating Devices, of which the following is a specification.

This invention relates to calculating devices of a simple type adapted for use as a tallying device in playing card games, such as pinochle, 500, etc., by adding the score, melds, bids, tricks, or the like, and mechanically registering the score. Objects of the invention are to save mistakes in addition, in keeping the score; to save the time usually taken to record the score; and, to provide a reliable tally of the score at all times.

These being among the objects of the present invention, the same consists of certain features of construction and combinations of parts to be hereinafter described, and then claimed with reference to the accompanying drawings illustrating a desirable embodiment of the invention, and in which:—

Fig. 1 is a plan view, showing all parts set to 0 (zero); and

Fig. 2 is a transverse section on the line A—A, Fig. 1.

Referring to the drawings, a base or flat board B is provided, which may be of any suitable shape. Mounted on a pivot D on the base is an indicator P¹, P². This indicator is preferably duplex, that is to say, the pivot D is located midway of the length of the strip or bar forming the indicator so as to provide two oppositely-directed pointers P¹, P², respectively.

The base B bears two graduated series of numerals as shown, extending in a circle concentric with the pivot D. One of the series of numerals runs from 0 (zero) half way around the circle, and preferably the said series consists of numerals which are progressive multiples of 5, the numeral 5 being placed at the graduation next the 0 (zero). The second series of graduated numerals occupies the other half of the circle, and consists of a repetition of the numerals in the other half, that is, they run from 5 up to 95, in progressive multiples of 5, the numeral 95 of the second series being placed the next graduation away from the 0 (zero) of the first series. It will be seen, therefore, that the two series of numerals referred to count up to 200 in the complete circle. The

two circularly-arranged series of numerals referred to are placed underneath the pointers P¹, P², so that on sweeping the pointers around the board, more or less, the extreme ends of the pointers, just inside of the circular series of numerals, may be set opposite any desired numeral of the two series. Each pointer P¹, P², is provided beyond its pointing extremity with a tooth P³, which is turned down towards the base B, the object of which will be explained later.

Mounted upon the pivot D so as to be upon the same axis as the indicator with its two pointers P¹, P², is a calculating-wheel A, which is preferably in the form of a flat circular disk of suitable material, such as celluloid, sheet metal, or the like. The calculating-wheel A is provided with two concentric series of numerals, each of which numerals is a multiple of the same factor which is used in the numerals on the base B, and the numerals of the said two series on the calculating-wheel A are graduated the same as the numerals on the base, so that any given numeral on the calculating-wheel A may be set opposite a certain numeral on the base. On the base the numerals in one half of the circle are repeated in the other half, but in the case of the calculating-wheel A the numerals run from 0 (zero) to 5, and so on, up to 195. Preferably, the numerals on the base progress in clockwise direction, and the outer series of numerals on the calculating-wheel A progress counter-clockwise, while the inner series of numerals on the calculating-wheel A progress in clockwise direction, or in the same direction as the numerals on the base. The 0 (zero) marks of the numerals on the base and the two series of numerals on the calculating-wheel are placed normally in a location which is determined by a toothed wheel to be now described.

A peripherally-toothed tallying- or totalizing-wheel C is mounted so as to turn on a pivot F on the base, said wheel being so placed that a tooth P³ of the pointers P¹, P² may be caused to engage with the teeth in either direction of sweep of the pointers. This totalizing-wheel C may be made of any suitable material, or the same material as the calculating-wheel A. Preferably, the totalizing-wheel C has frictional contact with the base B so as not to be revolved too easily, it being desired to revolve the same only through actuation by one of the

pointer-teeth P^3 . Said totalizing-wheel C has one series of teeth C^1 , and another series of teeth C^2 , which alternate with the teeth C , but all of the teeth are arranged in a circle at the periphery of the wheel C . When a totalizing-wheel C is used in connection with the specific indicator and calculating-wheel described, and in connection with the described system of numerals on the calculating-wheel and on the base B , it is desirable to have two alternating series of teeth C^1, C^2 on the totalizing-wheel, so that the totalizing-wheel may be caused to register, as in hundreds up to 2,000, said totalizing-wheel being actuated two teeth whenever the tooth of a pointer is caused to sweep past the totalizing-wheel. In the example shown, the series of teeth C^1 are provided opposite them with numerals 1 to 10 inclusive, and the series of teeth C^2 are provided with an inner series of numerals opposite them running from 11 to 20, the numeral 11 being opposite the tooth next following the 0 (zero) tooth on the tallying-wheel. The numerals on the tallying-wheel are caused to be set opposite a stationary indicator on the base B which is in the form of an arrow or the like.

The indicator comprising the two pointers P^1, P^2 is preferably composed of a strip of springy metal, for the purpose of enabling the indicator to be put under tension by the pivot D . To do so the pivot is passed through the flat strip of the indicator in assembling the device, and the indicator thereby caused to be bowed or set by the pivot, the pivot being fixed in position by a cotter pin or the like E^1 , which holds the indicator to its set. A washer E surrounds the pivot D between the perforated central portion of the indicator and the calculating-wheel A , so as to raise the indicator a suitable distance away from the calculating-wheel and to permit each to revolve freely without interference by the other.

In order to prevent the indicator from being turned too freely and to hold the same at the position where it is set, the ends of the pointers are provided with teats G which are adapted to register with and snap into, depressions G^1 in the base B . If the elements G, G^1 are employed, the depressions G^1 will of course be positioned in line with the numerals on the base. For a similar purpose, the base B is preferably provided with a series of teats H , which are adapted to be received in depressions H^1 in the calculating-wheel A . These teats H and depressions H^1 will hold the calculating-wheel in the position to which it may be turned and set.

Preferably surrounding the totalizing-wheel C there is a raised portion or guard ridge I on the base B . This raised portion I will serve to protect the totalizing-wheel C against accidental movement. Preferably,

the pointers P^1, P^2 are provided respectively with openings O^1, M^1 , and O^2, M^2 . The openings M^1, M^2 permit a reading of any numeral on the base opposite which the indicator may be set, while openings O^1, O^2 permit the numerals on the calculating-wheel which may be set opposite any given numeral on the base to be read through said openings.

The construction above described, or its equivalent, may be arranged in duplicate upon a single base or board, so that there will be one calculating device for home team, and another calculating device for a visiting team. In the specific embodiment of the invention shown it will be seen that the calculating-wheel is graduated on its outer circumference in 40 units of 5, marked thereon counter-clockwise so as to permit addition of 200 in one rotation in a clockwise direction. The base B is graduated in such case outside the circumference of the calculating-wheel in the same number of units, with the multiples of 5 marked on the base in a clockwise direction.

To use the calculating device, as in a game, begin the game with all parts set to 0 (zero). To add the initial score or meld (say 40) rotate the calculating-wheel A in a clockwise direction, bringing the graduation marked 40 thereon opposite the 0 (zero) on base B , and then the 0 (zero) or the arrow on calculating-wheel A will be opposite the graduation marked 40 on the base B . Next, rotate the indicator P^1, P^2 from 0 (zero) adjacent the tallying-wheel in a clockwise direction to the 40 already set. If the next score or meld is 60, again rotate the calculating-wheel A clockwise so that 60 thereon coincides with the indicator set at 40, at which time the 0 (zero) or arrow on the calculating-wheel will be opposite the 100 mark on base B . Then, the two scores 40 and 60 have been automatically added. Now move the indicator P^1, P^2 clockwise to coincide with the 100 set off by the calculating-wheel A and proceed as before. The indicator P^1, P^2 records at all times the total score in units of 5 (5 being the factor) up to 100. When the indicator has been moved far enough from the 0 (zero) on the base to indicate 100, 100 is automatically added by the engagement of a tooth of pointer P^2 with one of the teeth of the totalizing-wheel C , which in this case happens to be a hundreds tally. This will advance the totalizing-wheel from 0 (zero) to 1, and thus register 100. The indicator moves the totalizing-wheel for a distance of two teeth every half rotation of the indicator, that is, every 100 points of revolution. In the embodiment of the invention shown it will be seen that the totalizing-wheel C containing twenty-one teeth is graduated from 0 (zero) to 20, so that any

score up to 2000 is registered by the device, which admirably adapts this calculator as a score-adding and registering device for use in obtaining the tally in certain card games.

5 To subtract a default, the secondary or inner series of numerals on the calculating-wheel A are used, the graduations thereof being numbered from 5 to 200 in a clockwise direction on said wheel. To demonstrate 10 the operation, assume that the total score is 400, that is, the indicator P^1, P^2 pointing to 0 (zero) at the point on the base adjacent the totalizing-wheel, and the latter reads 4 and the default is 150. The calculating- 15 wheel A is rotated counter-clockwise until the graduation 150 in the inner series thereof coincides with the indicator at 400. The 0 (zero) arrow of calculating-wheel A will now be pointing to the numeral 50 on the 20 base B. The indicator is now moved counter-clockwise to coincide with the 0 (zero) arrow on the calculating-wheel A and the numeral 50 on the base B, and in so doing, the teeth of the indicator P^1, P^2 are meshed twice 25 with the teeth of the totalizing- or hundreds tally-wheel C, setting the latter back for two graduations from 4 to 2, so that the register now reads 250, and the default of 150 has been mechanically and automatically subtracted from 400. If more than 200 is to 30 be added or subtracted, say 350, 150 is first added or subtracted as above, and then a full revolution of the indicator P^1, P^2 is made, thus adding or subtracting, as the 35 case may be, the additional 200.

The use of the calculating-wheel A may be discontinued at will in adding and indicating a score, for simple melds or scores of 20, 50, 100, etc., can be readily added or subtracted by simply moving the indicator P^1, P^2 ahead or back these amounts, and then when a larger number like 185, etc. is to be added, the calculating-wheel A can again be employed.

45 It is obvious that a different system of numerals may be used throughout the device and other factors than 5 may be employed for the indicator and the calculating-wheel, and that the device may be otherwise modified as to its details without departing 50 from the scope of the invention as defined in the appended claims, and I, therefore, do not limit myself to the precise construction and system of numerals described and 55 shown.

What I claim as new is:

1. In a calculating device of the class described, the combination of a base, a resilient pointer pivoted thereon and provided 60 with a carrying tooth, the outer end of said pointer having frictional contact with said base, and said base bearing a graduated series of numerals concentric with the pivot of the pointer, and which run from zero 65 through progressive multiples of a factor

one graduation from the zero, and a rotatable, toothed, totalizing-wheel mounted on said base in position to permit the tooth of said pointer to engage its teeth, said wheel bearing a graduated series of numerals set 70 opposite its teeth and which run, in the same direction as the numerals on the base, from 1 up through progressive multiples thereof, said base having a stationary indicator for said totalizing wheel. 75

2. In a calculating device of the class described, the combination of a base, a pointer pivoted thereon and provided with a tooth, said base bearing a graduated series of numerals concentric with the pivot of the 80 pointer, and which run from zero through progressive multiples of a factor one graduation from the zero, and a rotatable, toothed, totalizing wheel mounted on said base in position to permit the tooth of said pointer 85 to engage its teeth, said wheel bearing a graduated series of numerals set opposite its teeth and which run, in the same direction as the numerals on the base, from 1 up through progressive multiples thereof, said 90 base having a stationary indicator for said totalizing wheel; with a calculating wheel mounted on the base to rotate concentrically with said pointer and bearing two concentric series of numerals, whereof the numerals of 95 each series are graduated the same as, and progress the same as, the numerals on the base, while the numerals of one series of said calculating wheel progress counter to the numerals of the other series. 100

3. In a calculating device of the class described, the combination of a base, an indicator pivoted thereon midway of its length and having two alined oppositely-extending pointers, each having a tooth, said base bearing two graduated series of numerals extending in a circle concentric with the pivot of said indicator, the numerals of one series in one-half of the circle running from zero 110 through progressive multiples of a factor one graduation from the zero, and the numerals of the other series in the other half circle being a repetition thereof from a corresponding factor back to the zero, and a 115 rotatable, toothed, totalizing wheel mounted on said base, in position to permit each tooth of said pointers to engage its teeth, there being one series of numerals on said wheel which are set opposite successive alternate 120 teeth and another series of numerals thereon which are set opposite the successive intermediate teeth, the numerals of the two series on said wheel progressing in the same direction as the numerals on the base from 1 up through progressive multiples thereof. 125

4. In a calculating device of the class described, a totalizing wheel provided with an odd number of peripheral, equi-distantly, spaced gear teeth and bearing opposite each tooth, except one, one of the numbers of one 130

of two series of numbers running upward from 1 as a factor, and progressing in multiples thereof, the numbers which read consecutively in each series being spaced apart 5 so as to skip alternate teeth.

5. In a calculating device of the class described; a base, an indicator having means at its midlength for revolubly mounting it on said base, and consisting of a straight 10 strip of springy material, in combination with means for bowing said indicator to give it a spring-set, the springy ends of said indicator forming oppositely extending

pointers and bearing frictionally on said base.

6. In a calculating device of the class described, the combination with a base, calculating means including several series of progressive numbers, using for example, 5 as a factor, and multiples thereof, and a duplex 20 pointer the ends of which have frictional contact with said base, of a toothed hundreds totalizing wheel operable by each of the pointers to advance said wheel two teeth or a hundred points.

MARSHALL ANGLE PURSEL.
